UNITED STATES PATENT OFFICE.

WILLIAM J. DEVERS, OF SCRANTON, PENNSYLVANIA, ASSIGNOR OF ONE-HALF TO MORGAN DAVIS, JR., OF SAME PLACE.

RAIL-JOINT.

SPECIFICATION forming part of Letters Patent No. 679,956, dated August 6, 1901.

Application filed April 27, 1901. Serial No. 57,825. (No model.)

To all whom it may concern:

Be it known that I, WILLIAM J. DEVERS, a citizen of the United States, residing at Scranton, in the county of Lackawanna and State 5 of Pennsylvania, have invented a new and useful Rail-Joint, of which the following is a specification.

The invention relates to improvements in rail-joints.

10 One object of the present invention is to improve the construction of rail-joints and to provide a simple, inexpensive, and efficient one adapted to afford a firm support for the ends of the rails and capable of carrying the 15 wheels of a train over the same and of preventing the wheels from contacting with and breaking down the ends of the rails.

A further object of the invention is to provide a device of this character adapted to 20 form practically a continuous rail to relieve a train of the jars, shocks, and vibrations incident to passing over the ends of ordinary rails.

The invention consists in the construction 25 and novel combination and arrangement of parts hereinafter fully described, illustrated in the accompanying drawings, and pointed out in the claims hereto appended.

In the drawings, Figure 1 is a perspective 30 view of a rail-joint constructed in accordance with this invention. Fig. 2 is a transverse sectional view. Fig. 3 is a detail view of the inner fish-plate. Fig. 4 is a similar view of the supporting-plate. Fig. 5 is a detail view 35 of the outer fish-plate.

Like numerals of reference designate corresponding parts in all the figures of the drawings.

1 and 2 designate inner and outer fish- 40 plates arranged at the inner and outer faces of rails 3 and secured to the same by bolts 4, passing through the fish-plates and through the webs of the rails in the usual manner, and these bolts, which are provided with suitable 45 nuts, may be of any desired number. The inner fish-plate 1 is provided with an outwardly-extending bottom flange 5, fitting against the bottom flange of the rail, and the inner face of the vertical portion of the inner 50 fish-plate is provided with upper and lower longitudinal ribs or enlargements 6 and 7,

fitting against the adjacent faces of the webs of the rails and arranged beneath the heads of the same and at the bottom flanges thereof. The ribs or enlargements 6 and 7 offset 55 the body portion of the vertical part of the inner fish-plate from the webs of the rails. The outer fish-plate is provided with a bottom flange 8, and it has a top or head 9 arranged at the outer side faces of the heads of the 60 rails and extending above the treads of the same and adapted to carry the wheels of a train over the ends of the rails without permitting them to contact with the same and forming practically a continuous rail, where- 65 by the jars and vibrations incident to the contact of the wheels of a train with the ends of the rails are avoided. The durability of the rails is also greatly increased, and the ends of the top or head 9 of the outer fish- 70 plate are beveled to enable the wheels of a train to readily ride up the same. The flange 8 of the fish-plate extends outward at the bottom, and the said outer fish-plate is also provided with an inwardly-extending bottom 75 flange 10, having its lower face arranged in the same inclined plane as the lower face of the inclined outer bottom flange 8. The top or head 9 of the outer fish-plate projects laterally from the same at the inner and outer 80 faces thereof, and the inwardly-projecting portion abuts against the adjacent side faces of the heads of the rails, as clearly shown in Fig. 2.

In order to enable the parts to be properly 85 positioned with relation to the rails, either in assembling the parts or when the outer fish-plate becomes worn, longitudinal strips 13 and 14 of thin sheet metal may be arranged as illustrated in Fig. 1 of the drawings. The 90 upper longitudinal sheet-metal strip is interposed between the top or head 9 and a longitudinal supporting-plate 15, which also supports the rails. The supporting-plate 15, which has an enlarged top portion, tapers to 95 toward its bottom and is interposed between the outer fish-plate and the webs of the rails and is provided at its inner face with upper and lower longitudinal ribs 16 and 17, located at the top and bottom of the webs of the rails 100 and fitting against the same. The top of the supporting-plate conforms to the configura-

tion of the lower faces of the heads of the rails, and the bottom is rounded to fit the bottom flanges of the rails. The lower portion of the supporting-plate is interposed between the bottom flange 10 of the outer face-plate and the webs of the rails. The lower strip 14 is arranged beneath the bottom of the outer fish-plate and coöperates with the upper strip 13 in slightly elevating the outer fish-plate. The openings for the bolts are designed to be of sufficient size to permit this adjustment of the outer fish-plate, and the ends of the longitudinal strips are bent against the adjacent portions of the outer fish-plate. Should it be desired to raise the outer fish-plate again, the strips 13 and 14 may be removed and thicker strips substituted for them. The bottom strip 14 may be provided with a longitudinal flange 18, which is interposed between the flange 10 and the supporting-plate. The upper strip 13 is preferably bent upward, and the ends of the flange 18 are bent outward horizontally.

It will be seen that the rail-joint is exceedingly simple and inexpensive in construction, that it strengthens, supports, and increases the durability of the rails, and that it forms practically a continuous unbroken rail and prevents the wheels of a train from coming in contact with and breaking down the ends of the rails.

What I claim is—

1. In a rail-joint, the combination with a pair of rails, of an inner fish-plate, an outer fish-plate provided with a head extending above the rails, said outer fish-plate being

also provided with an inwardly-extending bottom flange, and the tapering supporting-plate interposed between the outer fish-plate and the rails and supporting the heads of the rails and the top of the outer fish-plate, the bottom of the supporting-plate abutting against the bottom flange of the outer fish-plate and the web of the rails and resting upon the bottom flanges of the same, substantially as described.

2. In a rail-joint, the combination with a pair of rails, of an inner fish-plate, the outer fish-plate provided with a head, longitudinal strips arranged upon the bottom flanges of the rails and upon the top of the inner fish-plate and supporting the outer fish-plate to raise the same, and means for securing the fish-plates to the rails, substantially as described.

3. In a rail-joint, the combination with a pair of rails, of an inner fish-plate, an outer fish-plate provided with a head and having an inwardly-extending bottom flange, the supporting-plate interposed between the outer fish-plate and the rails, and the longitudinal strips arranged beneath the head and the inwardly-extending bottom flange of the outer fish-plate, substantially as described.

In testimony that I claim the foregoing as my own I have hereto affixed my signature in the presence of two witnesses.

WILLIAM J. DEVERS.
